Fig. 9.

FIGURE 1 is a top perspective view of a combined puzzle and container showing my new design.

FIGURE 2 is a top perspective view of the opposite side thereof.

FIGURE 3 is a top perspective view thereof with parts in exploded relationship.

FIGURE 4 is a top perspective view thereof with the internal pieces assembled in a different relationship.

FIGURE 5 is a top perspective view thereof with the internal pieces assembled in the same relationship as in FIGURE 4, but viewed from the opposite side.

FIGURE 6 is a top perspective view thereof with the internal pieces assembled in a relationship different from that of FIGURE 1 and different from that of FIGURE 4.

FIGURE 7 is a top perspective view thereof with the internal pieces assembled in the same relationship as in FIGURE 6, but viewed from the opposite side.

FIGURE 8 is a top perspective view thereof with the internal pieces assembled in a relationship different from that shown in FIGURE 1, different from that shown in FIGURE 4 and different from that shown in FIGURE 7.

FIGURE 9 is a top perspective view thereof with the internal pieces assembled in the same manner as illustrated in FIGURE 8, but viewed from the opposite side.

I claim:

The ornamental design for a combined puzzle and container, substantially as shown and described.
